Primary Examiner—Nelson C. Holtje[57] **CLAIM**

The ornamental design for a perpetual calendar-clock, as shown and described.

DESCRIPTION

FIG. 1 is a front elevational view of the perpetual calendar-clock showing my new design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The broken-line showings in FIG. 1 are environmental only and form no part of the claimed design.
